Des. 202,904
Patented Nov. 16, 1965

202,904

TOY FIREARM

Felix Gilbert, New York, N.Y., assignor to De Luxe
Reading Corp., Elizabeth, N.J., a corporation of New Jersey

Filed Feb. 11, 1965, Ser. No. 83,786

Term of patent 7 years

(Cl. D34—15)

FIG. 1 is a right side elevational view of a toy firearm, showing my new design;

FIG. 2 is a left side elevational view of the firearm;

FIG. 3 is a top plan view of the firearm;

FIG. 4 is a bottom plan view of the firearm;

FIG. 5 is a front elevational view of the firearm;

FIG. 6 is a rear elevational view of the firearm.

The essential features of my design reside in the full line portions shown.

I claim:

The ornamental design for a toy firearm, substantially as shown and described.
